UNITED STATES PATENT OFFICE

148,420

DESIGN FOR A RAG RUG

Jessie Jebiley and Saleem Haddad, Tenafly, N. J.

Application September 6, 1946, Serial No. 133,094

Term of patent 3½ years

(Cl. D92—21)

To all whom it may concern:

Be it known that we, Jessie Jebiley and Saleem Haddad, both citizens of the United States, residing at Tenafly, in the county of Bergen and State of New Jersey, have invented a new, original, and ornamental Design for a Rag Rug, of which the following is a specification, reference being had to the accompanying drawing, forming a part thereof.

In the drawing:

The figure is a plan view of a rag rug, showing our new design.

We claim:

The ornamental design for a rag rug, as shown.

JESSIE JEBILEY,
SALEEM HADDAD.
